(57) **CLAIM**

The ornamental design for a clip for dosing syringe as shown and described.

DESCRIPTION

1. Clip for dosing syringe
 Fig. 1.1 is a front perspective view of a clip for dosing syringe, showing my new design;
 Fig. 1.2 is an alternate front perspective view thereof;
 Fig. 1.3 is a side view thereof;
 Fig. 1.4 is another side view thereof;
 Fig. 1.5 is a top view thereof;
 Fig. 1.6 is a rear view thereof;
 Fig. 1.7 is a front view thereof;
 Fig. 1.8 is a rear perspective view thereof; and
 Fig. 1.9 is a bottom view thereof.
